UNITED STATES PATENT OFFICE.

J MONROE ALEXANDER, OF SPANISH FORK, UTAH.

TOE-PROTECTOR FORMER.

Application filed June 2, 1927. Serial No. 196,101.

The present invention relates to a device designed for forming leather protectors to be positioned over the toes of children's shoes to protect the toes of the shoes against wear.

An important object of the invention is to provide a device of this character which may be secured to a work bench and readily operated by moving the forming head into engagement with the leather under treatment, and finally exerting pressure on the forming head.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a sectional view through a former constructed in accordance with the invention.

Figure 2 is a plan view of the device.

Figure 3 is a plan view of the device, showing the lever in its elevated position.

Figure 4 is a fragmental plan view of the lever.

Referring to the drawing in detail, the device includes a body portion indicated generally by the reference character 5, the same being provided with an elongated cut out portion 6, in which one end of the link 7 is pivotally mounted. This link 7 is provided with a depending end portion 8 formed with an opening to receive a pin 9 that connects the link to the body portion.

At the opposite end of the link 7 is a right angled end portion 10 which is pivotally supported within the cut out portion 12 of the operating lever 13, by means of the pivot pin 11. The body portion 5 has its upper surface cut away adjacent to one end thereof, the cut away portion having a curved surface 14 shaped to conform to the toe of a shoe as clearly shown by Figures 2 and 3 of the drawing. As illustrated by Figure 2,

a head 15 is formed at one end of the lever 13, the head having a curved surface conforming to the shape of the curved surface 14 so that the curved end of the head will closely fit within the curved surface, to insure the proper shaping of a strip of leather positioned within the cut out portion of the body portion 5.

Formed on the upper surface of the head 15, and extending laterally therefrom, are wings 16 which have tapered forward edges 17 that are designed to contact with the leather under treatment to force the leather forwardly onto the body portion and hold the leather while the lever 13 is being moved downwardly in the act of forming or shaping the leather.

Securing screws 18 pass through suitable openings provided in the body portion and act to secure the body portion to a work-bench or the like insuring against movement thereof while the lever is being operated.

From the foregoing it will be seen that a strip of leather to be shaped, is softened by soaking the same in water or the like fluid, whereupon the strip of leather is placed over the cut out portion of the body and the lever moved to the limit of its upward position.

The lever is now moved downwardly, the forming head thereof being forced into engagement with the leather, causing the leather to take the shape of the cut out portion.

I claim:

1. In a device of the character described, a body portion having its upper surface cut away adjacent to one end thereof, the cut away portion defining a curved surface, a lever having a head curved to conform to the curvature of the cut away portion and adapted to clamp an article within the cut away portion to shape the article, and wings having tapered forward edges extending laterally from the head, the tapered edges of the wings adapted to engage an article positioned on the body portion to force the article into the body portion, and a link for connecting the lever to the body portion.

2. In a device of the character described,

a body portion having a cut away portion defining a curved surface, a lever having a head formed with a curved forward extremity adapted to fit within the curved surface of the body portion to shape an article positioned therein, lateral members on the head adapted to contact with an article positioned

on the body portion to move the article forward, and a link for connecting the lever and body portion.

In testimony that I claim the foregoing as my own, I have hereto affixed my signature.

"J" MONROE ALEXANDER.
